(Cl. D86—9)

To all whom it may concern:

Be it known that I, Frederick M. Breen, a citizen of the United States, residing at Westchester, in the county of Westchester and State of New York, have invented a new, original, and ornamental Design for a Combined Music Box and Container or Similar Article, of which the following is a specification, reference being had to the accompanying drawing, forming part thereof.

In the drawing

Fig. 1 is a top plan view of a combined music box and container or similar article, showing my new design;

I claim:

The ornamental design for a combined music box and container or similar article, substantially as shown.

FREDERICK M. BREEN.
